UNITED STATES PATENT OFFICE.

ARNOLD D. COLEMAN, OF CHICAGO, ILLINOIS.

MACHINE FOR SEAMING HEADS ON CANS.

No. 881,500.

Specification of Letters Patent.

Patented Sept. 18, 1906.

Application filed May 22, 1905. Serial No. 261,603.

To all whom it may concern:

Be it known that I, ARNOLD D. COLEMAN, a citizen of the United States, and a resident of Chicago, in the county of Cook and State of Illinois, have invented certain new and useful Improvements in Machines for Seaming Heads on Cans; and I do hereby declare that the following is a full, clear, and exact description of the same, reference being had to the accompanying drawings, and to the letters of reference marked thereon, which form a part of this specification.

Heretofore machines have been constructed for this purpose in which the cans are supported with the head in place in oppositely-disposed revolving chucks, which hold the body and the head flanges against a stationary die-bar to form and close the seam. In machines of this class heretofore rolling pressure is exerted immediately upon the can itself to force the same against the die-bar, and various devices have been used for this purpose. Where such rolling pressure is exerted directly upon the can, the cans are likely to be injured or at least imperfectly sealed, owing to the sides of the can yielding somewhat from the pressure.

The object of this invention is to close the can by rolling the can-body and the head-flanges directly against a fixed die-bar by means of oppositely-disposed rolling or revolving chucks on one of which rolling pressure is exerted by means of a chain belt having continuous movement.

The invention consists in the matter hereinafter described, and more fully pointed out in the appended claims.

As shown in the drawings, Figure 1 is a top plan view of a machine embodying my invention. Fig. 2 is an enlarged detail of one link of the pressure-transmitting chain belt. Fig. 3 is a detail section illustrating the construction of the driving-sprocket for the chain. Fig. 4 is a similar view illustrating the construction of the idler-sprocket therefor. Fig. 5 is an elevation taken at the feed end of the machine. Figs. 6 to 9 are enlarged fragmentary detail views illustrating the construction of the chucks and the relation of the fixed die and pressure-chain therewith in forming and closing the seam. Fig. 10 is a side elevation of a machine embodying my invention.

As shown in said drawings, said machine

55 comprises a base or frame A, having thereon upright standards B and B', upon which the operating mechanism is carried. A driving-shaft a is provided at one end of the machine and provided with tight and loose pulleys a' and a'' , and, as usual, said driving-shaft is provided on its inner end with a pinion a^3 , which meshes with a gear a^4 , secured on a transverse shaft a^5 . A bevel-gear a^6 is also provided on said shaft a^5 , which meshes with the bevel-pinion a^7 on a vertical transverse shaft a^8 , on the upper end of which is a pinion a^9 , meshing with a gear a^{10} , rigidly secured on a shaft a^{11} , journaled in brackets a^{12} , which are rigidly secured centrally at the end of a horizontal frame C, supported on the top of the standards B'. Beneath said gear a^{10} and secured on the same shaft is a sprocket-wheel a^{13} , below which is secured a disk or wheel a^{14} . Said gear a^{10} and the disk or wheel a^{14} are each provided with a shoulder or peripheral rib on their inner side adapted to afford a support for the chain E, whereby the chucks are engaged. At the opposite end of the frame C is provided a bracket c, corresponding with the bracket a^{12} , and journaled therein is a shaft c' , having thereon a sprocket-wheel c^2 , an upper disk c^3 , and a lower disk c^4 , each provided with an inner rib near the periphery similar to those shown near the periphery of the gear a^{10} and disk a^{14} .

70 The chain or link belt E is trained around said sprocket-wheels and is supported between the gear a^{10} and disk a^{14} at one end of the machine and the disks c^3 and c^4 at the other and comprises a plurality of duplicate 75 interchangeable links E', having on the rear side at one end two apertured knuckles e and at the other one apertured knuckle e' of a thickness equal to the distance between the knuckles e, so that the single knuckle of one 80 link fits between and is pintled with the knuckles of the next adjacent link. Extending outwardly from the middle of the rear side of the link is a tooth or projection e^2 , which, together with the knuckles, engages the 85 sprockets. Said chain for the entire length of its run between the sprocket-wheels on the inner side of the frame fits against the frame C, with the knuckles and teeth thereof projecting into a longitudinal groove therein. 90 (Not shown.)

95 The front side of each link is approximately rectangular and affords square ends, so that the inner run of the chain between the 100 sprocket-wheels forms a continuous straight 105

110

face. A central longitudinal rib e^3 is provided on the face of each link, and secured beneath the same is a hardened-steel friction or wear plate e^4 , the outer edges of which are in alignment in the inner run of the chain or belt and afford a working face adapted to engage the upper chuck, revolving the same.

Supported on the standards B and rigidly secured thereto is a die-bar F, provided with a longitudinal rib f on the under side, against which and rigidly secured to the die-bar is the die f', comprising a strip or bar of steel f', extending the length of the die-bar and providing a projecting flat edge f² opposite the wear-plate e⁴, against which the top of the chuck is engaged. Beneath said projecting edge the die is shaped for engagement by the can-body and head-flanges and is shaped to form and progressively close the seam as the flanges are rolled thereagainst. As shown, said die first for a part of its length affords a downwardly-directed approximately right-angled shoulder f³ to turn down the projecting edge of the head-flange over the body-flange. This is succeeded by a die-face having an under projecting lip f⁴, as shown in Fig. 7, succeeding which is an under beveled die-face f⁵, provided, as shown in Fig. 8, which partly closes the seam, and by a right-angled shoulder f⁶ in Fig. 9, which completely closes the seam.

As shown, transverse carrying-bars H are supported across the top of the die-bar F, and at the inner and the outer end of each carrying-bar parallel downwardly-extending ends h and h' are provided, in which are horizontally secured inwardly-facing parallel channel-bars h² and h³, the lower flanges of which afford tracks on each side of the die-bar and somewhat above the same.

Journalized at each end of the machine on the standards B are the vertical shafts H' and H², respectively. A beveled gear h¹⁰ is secured on the lower end of the shaft H' and meshes with a like gear h¹¹, feathered on the transverse driving-shaft a⁵. A yoke h¹², which also affords the bearing for that end of the shaft a⁵, acts to slide said gear on said shaft with the movement of the standards B, which are adjustable transversely of the machine for varying sizes of cans, thus keeping said gears always in mesh. Secured on each of said shafts H' and H² at a level with the tracks is a sprocket-wheel h⁶, about which a link chain H³, comprising plates of metal pintled together in a familiar manner, is trained. Said chain H³ carries the upper chucks. Alternate links in the chain are provided with rollers h¹³, journaled centrally on each side thereof, which run on the track afforded by the inwardly-directed lower flanges of said channels, thereby reducing friction while carrying the chain horizontally. Extending centrally through each intermediate link and at right angles with the axis of said rollers h¹³

is a rotatable cylindric stem h⁷, slidably secured therein. On the lower end of each stem is secured a chuck h⁸, comprising, as shown, a circular plate or disk, the underface of which is of a diameter adapted to fit closely into the recess in the can-head when the same is placed upon the can. At a point in said chuck corresponding with the top of the seam when formed and also with the oppositely-projecting edges of the wear-plates e⁴ of the chain E and the projecting edge f² of the die the chuck is reduced in diameter, as shown in Figs. 6 to 9, inclusive, thus affording a shoulder over which the wear-plate and edge of the die engage to press the chuck down upon the can and roll the flange against the die. The stem h⁷, as shown, is provided with an enlarged head, which prevents the stem falling through the apertures of the chain when the can is removed. The sprocket-wheels h⁶, over which the chuck-carrying chain H³ is trained, are each constructed with outwardly-directed arms having notches in the end thereof adapted to engage the pintles between the links of the chain. The lower chain H⁴ corresponds with the upper chain H³ in construction and is trained around sprocket-wheels h¹⁴, secured in the shafts H' and H², and carries the lower chucks L.

Secured on the standards B and extending longitudinally of the machine and directly beneath the channel-iron tracks of the upper chuck are ways i⁴ and i⁵, each having a longitudinal groove therein and flat upper faces and at the rear or discharge end of the machine having an inclined end i⁶, as shown in Fig. 10. The chain H⁴, trained around the lower sprocket-wheels h¹⁴, is constructed similarly with the chain H³ for the upper chucks and, as shown, is provided at intervals in its length with rollers k, which track on the flat faces of the ways and support the weight of the chain H⁴, reducing the friction to a minimum. The lower chucks L are constructed similarly with the chucks h⁸ and comprise upwardly-facing cylindric disks, which engage in the recess in the can-bottom to support the can and are each provided with a spindle i, slightly engaged through the center of alternating links in the chain H⁴. Said spindles are rounded at the lower end to engage in said track or grooves in the ways.

The operation is as follows: The cans are filled into the machine at the end remote from the drive end and may be fed either manually or automatically and may be previously filled, if desired. The can is placed upon one of the lower chucks L and beneath the upper corresponding chuck, and as they pass into the machine the wear-plates e⁴ on the chain E engage above the upper chuck and against the shoulder thereon, forcing the same against the plate f² on the die, thus rolling the head-flange and the can-body along the die, forming and closing the seam. The

cans being carried through the machine in an upright position may be filled before insertion into the machine, if desired, and owing to the relatively slow rotation thereof none of the contents will be spilled therefrom. Furthermore, inasmuch as there is no pressure exerted on the can-body by the rotating mechanism there is no danger of injuring the cans or forming the seams imperfectly.

10 Inasmuch as many details of construction may be varied without departing from the principles of my invention, I do not purpose limiting this application for patent otherwise than necessitated by the prior art.

15 I claim as my invention—

1. In a machine of the class described the combination with chucks adapted to grip a can and its head therebetween, of a stationary die positioned to be engaged by the head.
- 20 and body flanges and a continuously-movable pressure device acting against the chuck to roll the chuck on a part connected with the die thereby rotating the can and head with the flanges thereof in the die, closing the seam.
- 25 2. The combination with oppositely-arranged movable chucks adapted to grip a can and its head therebetween, of a fixed die adjacent the path of movement thereof and adapted to be engaged by the body and the
- 30 head flanges, a continuously-movable chain acting to engage one of the chucks and force the same inwardly and against a part on the die, thereby rotating the chucks and the can and closing the seam.
- 35 3. A machine of the class described comprising rolling oppositely-disposed chucks adapted to receive a filled can therein in upright position and to clamp the can-head into place thereon, a die having a part thereon adapted to engage one of the chucks and means engaging one of the chucks only and acting to rotate the same and roll the can-head and the body-flanges against the die, thereby acting to seam the head on the can
- 40 without soldering.
- 45 4. A machine adapted to head and seam filled cans, comprising chucks adapted to engage the cans and clamp a head on each, a fixed die against which projecting flanges of the head and the can-body are rolled to afford a locked seam, a part thereof adapted to engage against the side of one chuck and means acting on one of the chucks to rotate the flanges against the die.
- 50 5. In a machine adapted for seaming heads on filled cans, oppositely-disposed upper and lower chucks, between which a filled can and the head thereof are rigidly clamped, a die-bar having a part adapted to engage over a part on the upper chuck and against which said chuck has rolling engagement, a chain belt also in positive engagement with said chuck and acting to roll projecting edges of the head and the can against the die closing
- 55 the seam, and means supporting the chucks

and adapted to afford free rotation and also vertical movement of the same.

6. In a machine for heading filled cans, upper and lower chucks, the one to support a can, the other to grip the head thereon, a fixed die having an upper projecting edge lapping over the top chuck and bearing against a shoulder thereon, means supporting the lower chuck and a continuously-moving pressure-chain having positive bearing on the top chuck and forcing the seam against the die and closing the seam by rotating the can.

7. In a machine of the class described, a chuck adapted to support a can in upright position, a complementary chuck adapted to engage a head thereon, a fixed die, means engaging against the last-named chuck only, for revolving the chucks and can, forcing the seam against the die, and chains spacing the chucks a uniform distance apart.

8. In a machine for heading filled cans, oppositely-disposed rotative chucks, a part of which are provided with shoulders thereon, near their periphery, a die-bar, a chain adapted to travel longitudinally of said bar, a longitudinal rib thereon adapted to overlap said shoulders and hold the chuck in positive engagement with the die-bar and rotate the can to close the seam.

9. In a machine for seaming heads on cans, the combination with oppositely-disposed upper and lower chucks, of chains adapted to carry said chucks, guide-tracks for said chains, a stationary die adjacent the upper chucks and means adapted to engage said upper chucks peripherally and rotate them against the die.

10. In a machine of the class described the combination with standards of a die thereon, a track depending from each side of said die, sprocket-wheels journaled at each end of said die, a sprocket-chain thereon adapted to travel in said tracks, chucks rotatively engaged on said chains, a chain carried adjacent said chucks and provided on its outer face with a continuous rib adapted to engage said chucks and rotate them against the die and a plurality of chucks movably supported below the aforesaid chucks.

11. In a machine of the class described the combination with standards of a frame rigidly engaged thereon, a sprocket-wheel journaled at each end of said frame, a disk at each side of each wheel affording grooved guides, a pressure-chain driven by said wheels and affording an outwardly-directed rib, a stationary die, a lower chuck-carrying chain, a plurality of chucks thereon adapted to support the cans in a vertical position, an upper chuck-carrying chain and chucks thereon, adapted to engage the top of the cans and to be rolled by the pressure-chain along the face of the die.

12. In a machine of the class described the

combination with upper and lower chuck-
carrying chains of chucks journaled therein,
a die-bar extending longitudinally of the ma-
chine, a die-plate on the under face thereof
5 and projecting inwardly therefrom and en-
gaging on the top of the upper chucks, a die-
face on said plate and progressively changing
in form longitudinally thereof, a pressure-
chain adapted to rotate said chucks against

the die-plate and means supporting said 10
chain opposite the bar and parallel therewith.

In testimony whereof I have hereunto sub-
scribed my name in the presence of two sub-
scribing witnesses.

ARNOLD D. COLEMAN.
